(57) CLAIM

The ornamental design for an arm celebration instrument, as shown and described.

DESCRIPTION

FIG. 1 is an Upper Right Perspective view of an arm celebration instrument, on an arm, showing my new design; FIG. 2 is a Right Side Elevation view thereof;

FIG. 3 is a Left Side Elevation view thereof;

FIG. 4 is a Front Elevation view thereof;

FIG. 5 is a Rear Elevation view thereof;

FIG. 6 is a Top Plan view thereof; and,

FIG. 7 is a Bottom Plan view thereof.

The broken lines shown in FIG. 1 illustrating a hand and an arm is included to show environment and form no part of the claimed design.

1 Claim, 5 Drawing Sheets
